UNITED STATES PATENT OFFICE.

ARTHUR M. McNICHOL, OF YORKTON, SASKATCHEWAN, CANADA.

SAFETY-RAZOR.

1,199,706.

Specification of Letters Patent.

Patented Sept. 26, 1916.

Application filed June 22, 1915. Serial No. 35,723.

To all whom it may concern:

Be it known that I, ARTHUR M. McNICHOL, a subject of the King of Great Britain, residing at Yorkton, in the Province of Saskatchewan and Dominion of Canada, have invented new and useful Improvements in Safety-Razors, of which the following is a specification.

The invention relates to safety razors, and 10 more particularly to the class of automatic safety razors.

The primary object of the invention is the provision of a safety razor wherein the blade thereof is in strip form and adapted to automatically move across the working face of the holder so as to effect an angular cutting action when the razor is drawn over the face for shaving purposes.

Another object of the invention is the provision of a razor of this character wherein the strip is made flexible and endless so that it will be guided over a pair of rollers to present a continuous cutting edge movable under the action of a spring for effecting 25 the angular cutting operation.

A further object of the invention is the provision of a razor of this character which is novel in form to assure a positive operation and a fresh cutting edge during the 30 continued use thereof.

A still further object of the invention is the provision of a razor of this character which is simple in construction, reliable and efficient in operation, and inexpensive in 35 manufacture.

With these and other objects in view, the invention consists in the construction, combination and arrangement of parts as will be hereinafter fully described, illustrated in 40 the accompanying drawing, and pointed out in the claim hereunto appended.

In the drawing:—Figure 1 is a side elevation of a razor constructed in accordance with the invention. Fig. 2 is an end elevation thereof with the housing broken away. Fig. 3 is a sectional view on the line 3—3 of Fig. 1. Fig. 4 is a sectional view on the line 4—4 of Fig. 1.

Similar reference characters indicate corresponding parts throughout the several views in the drawing.

Referring to the drawing in detail, 5 designates the handle and 6 the housing which constitutes the holder for the razor blade, 55 the same being connected with the handle 5 so that the latter can be rotated for the

winding of a coiled main spring 7 which is inclosed within a case 8 rotatably journaled within the housing 6, the spring being fixed to the stem or handle 5 and the casing 8, respectively. Formed on the casing 8 at its periphery are gear teeth 9 which serve as the main driving element, and meshes with a gear 10 which also meshes with a driven gear 11 fixed to one of a pair of axles 12 60 journaled in spaced parallel relation to each other in opposite cheeks of the housing 6. The gear 10 meshes with the pinion 12 which is connected with a suitable speed regulator 13 for controlling the action of the spring 70 when the razor is in use. Fixed to the axles 12 are guide pulleys 14 over which is trained an endless flexible cutting blade 15, the same being acted upon by means of a tightener 16 of any approved form, which serves to hold 75 the blade taut. The outer stretch of the blade 15 travels without the working face 17 which carries a guard portion 18 of any ordinary form adapted to shield a thin blade in cutting position. The handle 5 is provided with a suitable ratchet wheel 19 with which engages a ratchet pawl 20 pivoted to the handle 6 and suitably held in working relation to the ratchet wheel for the locking of the handle to prevent the turning thereof 80 in one direction to resist the tension of the spring 7 when wound.

When the spring 7 is wound by the turning of the handle in the reverse direction the said spring acts upon the gears 10 and 11 for the driving of the blade 15 across the working face of the housing 6 so that when the razor is in use the blade will effect a continuous angular cutting action.

From the foregoing description, taken in connection with the accompanying drawing, the construction and manner of operation of the device will be clearly understood, and therefore a more extended explanation has been omitted.

What is claimed is:—

A safety razor comprising a substantially equilateral triangular shaped housing having a guard formed in one straight side thereof, pulleys journaled interiorly of the 105 housing an endless blade trained over the pulleys and having a sharpened edge movable beneath the guard, a handle rotatably journaled in the housing, a coiled main spring having one end fixed to the stem, a 110 spring casing loosely journaled upon the stem interiorly of the housing and having

- the opposite end of the spring fixed thereto, gear connections between the casing and one of the pulleys, a ratchet wheel mounted on the stem, and a locking pawl pivoted to 5 the housing and engageable with the ratchet wheel to lock the stem against rotation in one direction.

In testimony whereof I affix my signature in presence of two witnesses.

ARTHUR M. McNICHOL.
